(57) **CLAIM**

The ornamental design for a caulking tube cap, as shown and described.

DESCRIPTION

FIG. 1 is an isometric view of a caulking tube cap showing my new design;

FIG. 2 is a front elevation view thereof, the left side, right side, and rear views being identical thereto;

FIG. 3 is a top plan view of the caulking tube cap of FIG. 1; and,

FIG. 4 is a bottom plan view thereof.
